UNITED STATES PATENT OFFICE.

FREDERICK A. SCHWARTFAGER, OF CHICAGO, ILLINOIS.

SHOE-POLISHING APPARATUS.

1,232,857.

Specification of Letters Patent. Patented July 10, 1917.

Application filed October 7, 1916. Serial No. 124,218.

To all whom it may concern:

Be it known that I, FREDERICK A. SCHWARTFAGER, citizen of the United States, residing at Chicago, in the county of Cook 5 and State of Illinois, have invented a certain new and useful Improvement in Shoe-Polishing Apparatus, of which the following is a full, clear, concise, and exact description, reference being had to the accompanying drawings, forming a part of this 10 specification.

My invention relates to shoe polishing apparatus and employs a foot piece and a wiper mounted adjacent the foot piece 15 whereby a shoe placed upon the foot piece may be polished.

In the preferred embodiment of the invention the foot piece is operated in a downward direction by the pressure of the foot 20 thereupon and is restored to its upper position by means of a retractile spring.

The wiper employed is preferably in the form of a band of cloth or other suitable polishing material and there is provided in 25 conjunction with this cloth wiper a means for forming a bight in the wiper which changes correspondingly to the changing positions of the foot piece in its vertical travel and in which shifting bight the shoe 30 is disposed. The ends of the wiper are stationary in the operation of the apparatus and their anchorages are nearly in line with the foot piece whereby the bight that receives the shoe or the portion of the wiper 35 engaging the shoe is under substantially uniform tension through the range of travel of the foot piece, these normally stationary anchorages of the ends of the wiper and their substantial alinement with the foot 40 piece being important irrespective of the means for forming the shifting shoe receiving bight in the wiper. One end of the wiper is equipped with a tension producing device that is desirably in the form of a spring and in order that the tension may be adjustable, the spring has one end connected with one end of the wiper and its other end connected with an adjustable arm that may be moved to different positions to adjust the 45 tension of the spring and the consequent pressure of the wiper upon the shoe being polished.

I will explain my invention more fully by reference to the accompanying drawing showing the preferred embodiment thereof and in which Figure 1 is a view in side elevation showing the shoe in position to be 50

polished; Fig. 2 is a front view of the structure as it appears in Fig. 1; and Fig. 3 is a sectional plan view on line 3-3 of 60 Fig. 2.

Like parts are indicated by similar characters of reference throughout the different figures.

The foot piece 1 is desirably formed of 65 strap iron and has an upward extension 2 that is secured to the lower end of a restor- 70 ing or retractile coil spring 3 whose upper end is secured to a stationary anchorage 4. The foot piece forms the upper side of a 75 frame that has remaining sides 5, 6 and 7, the frame side 7 being continued along the side of the extension 2 to which it is riveted. The frame side 7 carries a flattened sleeve 8 which is thus attached to the foot piece 1 80 and whose bore receives an upright guide 9, the anchorage 4 and the guide 9 being desirably integrally formed out of a piece of strap iron which is anchored at intervals to a suitable support 10 terminating in a pedestal 11 at its lower end and in a handle 12 at its upper end, the handle being provided for the grasp of the user of the apparatus to enable him to steady himself upon one foot while the shoe upon the other is being polished. By downward pressure upon the 85 foot piece it may be depressed against the force of the spring 3 and when this pressure is sufficiently removed the spring 3 will draw the foot piece upwardly. By alternate 90 downward pressure and relief of such pressure the foot piece may be rapidly recipro- 95 cated in a substantially vertical direction. This reciprocation is effected in the presence of a wiper that will rub against the shoe, 100 indicated at 13, that is upon the foot piece, this wiper being desirably in the form of a band 14 that is preferably made of cloth. This band is desirably formed with a loop 105 15 at its lower end, through which the sta- tionary anchorage 16 is passed, this station- 110 ary anchorage being desirably a continua- tion of the strap iron out of which the anchorage 4 and the guide 9 are formed. A normally stationary anchorage 17 is provid- ed for the upper end of the band, the anchor- 115 ages 16 and 17 being substantially in aline- ment with the foot piece 1 throughout the range of vertical movement of the latter.

By this arrangement the band or wiper is maintained in frictional contact with the shoe being polished, the pressure of this frictional contact being substantially constant. In the preferred embodiment of the

invention the upper end of the wiping band receives the base of a stirrup 18 which is connected with the anchorage 17 by means of coil spring 19, this spring supplying the proper tension to the wiping band. The 5 tension of the spring 19 is desirably adjustable to which end the anchorage 17 is preferably in the form of an arm to whose outer end the upper end of the coil spring 19 is attached and whose inner end is pivotally 10 secured to the support 10 at 20. An upright rack bar 21 depends from the anchorage 4 and is positioned between the pivot and the upper end of the spring 19, the 15 anchorage arm 17 being engageable with the different teeth upon the rack bar to regulate the tension of the spring 19; said arm being movable in a vertical plane.

A bight forming element or bar 22, preferably non-rotatable, is secured at the outer 20 end of a bracket 23 that is carried by and projects from the frame sides 5, 7 so as to travel with the foot piece. The bight forming element 22 is desirably rounded and the 25 wiping band is sinuously disposed over the foot piece 1 where the shifting shoe receiving bight 13¹ is formed and over the element 22 where another bight 22¹ is formed, and, as this bight forming element is below 30 the level of the foot piece 1, the top and sides of the front of the shoe and the toe of the shoe 13 are snugly received in the bight 13¹ so that all these portions of the shoe are 35 subject to frictional engagement by the wiping band to polish these shoe portions as the shoe is rapidly elevated and lowered. In this polishing operation the tension to 40 which the spring 19 is adjusted is not modified materially owing to the substantial alinement of the foot piece 1 and the anchorages 16 and 17. In order to prevent the 45 wiping band from slipping from the bight forming element 22 the sides of the bracket 23 are joined by a cross piece 24, a slot being established between the cross piece and the bight forming element 22 through which the wiping band passes.

In the use of the apparatus the anchorage 50 arm 17 is lowered to a point where the tension of the spring 19 is totally relieved and sufficient slack is afforded in the wiping band readily to permit of the interposition 55 of the shoe to be polished between the wiping band and the foot piece whereafter the anchorage arm 17 is raised into engagement with that tooth upon the vertical rack bar 21 that will enable the spring 19 to place the desired degree of tension upon the wiping band to produce the required polishing 60 pressure of this band upon the shoe being polished.

While I have herein shown and particularly described the preferred embodiment of my invention I do not wish to be limited to the precise details of construction shown as

changes may readily be made without departing from the spirit of my invention, but having thus described my invention I claim as new and desire to secure by Letters Patent the following:—

1. A shoe polishing apparatus including a vertically reciprocable foot piece operable by a foot, placed thereupon, in a downward direction; a spring for moving the foot piece upwardly; a wiping band disposed adjacent the path of travel of the foot piece and having normally stationary anchorages; a bight forming element moving with the foot piece and forming a bight in the wiping band above the foot piece for receiving the shoe that is upon the foot piece, a tension spring for supplying tension to the wiping band; and means whereby the tension of the tension spring may be adjusted. 70

2. A shoe polishing apparatus including a vertically reciprocable foot piece operable by a foot, placed thereupon, in a downward direction; a spring for moving the foot piece upwardly; a wiping band disposed adjacent the path of travel of the foot piece and having normally stationary anchorages; a bight forming element forming a bight in the wiping band above the foot piece for receiving the shoe that is upon the foot piece; a tension spring for supplying tension to the wiping band; and means whereby the tension of the spring may be adjusted. 85

3. A shoe polishing apparatus including a vertically reciprocable foot piece operable by a foot, placed thereupon, in a downward direction; a spring for moving the foot piece upwardly; a wiping band disposed adjacent the path of travel of the foot piece; a bight forming element moving with the foot piece and forming a bight in the wiping band above the foot piece for receiving the shoe that is upon the foot piece; a tension spring for supplying tension to the wiping band; and means whereby the tension of the tension spring may be adjusted. 100

4. A shoe polishing apparatus including a vertically reciprocable foot piece operable by a foot, placed thereupon, in a downward direction; a spring for moving the foot piece upwardly; a wiping band disposed adjacent the path of travel of the foot piece; a bight forming element forming a bight in the wiping band above the foot piece for receiving the shoe that is upon the foot piece; a tension spring for supplying tension to the wiping band; and means whereby the tension of the tension spring may be adjusted. 115

5. A shoe polishing apparatus including a vertically reciprocable foot piece operable by a foot, placed thereupon, in a downward direction; a spring for moving the foot piece upwardly; a wiping band disposed adjacent the path of travel of the foot piece and having normally stationary anchorages; a bight forming element moving with the 130

foot piece and forming a bight in the wiping band above the foot piece for receiving the shoe that is upon the foot piece; and a tension spring for supplying tension to the 5 wiping band.

6. A shoe polishing apparatus including a vertically reciprocable foot piece operable by a foot, placed thereupon, in a downward direction; a spring for moving the foot piece 10 upwardly; a wiping band disposed adjacent the path of travel of the foot piece and having normally stationary anchorages; a bight forming element forming a bight in the wiping band above the foot piece for receiving the shoe that is upon the foot piece; and a tension spring for supplying tension to the 15 wiping band.

7. A shoe polishing apparatus including a vertically reciprocable foot piece operable by a foot, placed thereupon, in a downward direction; a spring for moving the foot piece upwardly; a wiping band disposed adjacent the path of travel of the foot piece; a bight forming element moving 20 with the foot piece and forming a bight in the wiping band above the foot piece for receiving the shoe that is upon the foot piece; and a tension spring for supplying tension to the wiping band.

8. A shoe polishing apparatus including a vertically reciprocable foot piece operable by a foot, placed thereupon, in a downward direction; a spring for moving the foot piece upwardly; a wiping band disposed adjacent the path of travel of the foot piece; a bight forming element forming a bight in the wiping band above the foot piece for receiving the shoe that is upon the foot piece; and a tension spring for supplying tension 35 to the wiping band.

9. A shoe polishing apparatus including a vertically reciprocable foot piece operable by a foot, placed thereupon, in a downward direction; a spring for moving the foot piece upwardly; a wiping band disposed adjacent the path of travel of the foot piece and having normally stationary anchorages; and a bight forming element moving 45 with the foot piece and forming a bight in the wiping band above the foot piece for receiving the shoe that is upon the foot piece.

10. A shoe polishing apparatus including a vertically reciprocable foot piece operable by a foot, placed thereupon, in a downward direction; a spring for moving the foot piece upwardly; a wiping band disposed adjacent the path of travel of the foot piece and having normally stationary anchorages; and a bight forming element forming 55 a bight in the wiping band above the foot piece for receiving the shoe that is upon the foot piece.

11. A shoe polishing apparatus including

a vertically reciprocable foot piece operable by a foot, placed thereupon, in a downward direction; a spring for moving the foot piece upwardly; a wiping band disposed adjacent the path of travel of the foot piece; and a bight forming element moving with the foot piece and forming a bight in the wiping band above the foot piece for receiving the shoe that is upon the foot piece. 65

12. A shoe polishing apparatus including a vertically reciprocable foot piece operable by a foot, placed thereupon, in a downward direction; a spring for moving the foot piece upwardly; a wiping band disposed adjacent the path of travel of the foot piece; and a bight forming element forming a bight in the wiping band above the foot 70 piece for receiving the shoe that is upon the foot piece. 75

13. A shoe polishing apparatus including a reciprocable foot piece; a wiping band disposed adjacent the path of travel of the foot piece and having normally stationary anchorages; a bight forming element moving with the foot piece and forming a bight in the wiping band above the foot piece for receiving the shoe that is upon the foot piece; and a tension spring for supplying tension 80 to the wiping band. 85

14. A shoe polishing apparatus including a reciprocable foot piece; a wiping band disposed adjacent the path of travel of the foot piece; a bight forming element moving with the foot piece and forming a bight in the wiping band above the foot piece for receiving the shoe that is upon the foot piece; and a tension spring for supplying tension 95 to the wiping band. 100

15. A shoe polishing apparatus including a reciprocable foot piece; a wiping band disposed adjacent the path of travel of the foot piece and having normally stationary anchorages; and a bight forming element moving with the foot piece and forming a bight in the wiping band above the foot piece for receiving the shoe that is upon the foot piece. 105

16. A shoe polishing apparatus including a reciprocable foot piece; a wiping band disposed adjacent the path of travel of the foot piece; and a bight forming element moving with the foot piece and forming a bight in the wiping band above the foot piece for receiving the shoe that is upon the foot piece. 110

In witness whereof, I hereunto subscribe my name this fifth day of October A. D., 120 1916.

FREDERICK A. SCHWARTFAGER.
